CLAIM

The ornamental design for a probe holder portion of a console as shown and described.

DESCRIPTION

FIG. 1 is a front, right side perspective view of a first embodiment of a probe holder portion of a console showing our new design.

FIG. 2 is an enlarged, partial view of the perspective view of the probe holder portion of a console of FIG. 1.

FIG. 3 is a front view of the probe holder portion of a console of FIG. 1.

FIG. 4 is a back view of the probe holder portion of a console of FIG. 1.

FIG. 5 is a right side view of the probe holder portion of a console of FIG. 1.

FIG. 6 is a left side view of the probe holder portion of a console of FIG. 1.

FIG. 7 is a top view of the probe holder portion of a console of FIG. 1.

FIG. 8 is a front, right side perspective view of a second embodiment of a probe holder portion of a console showing our new design.

FIG. 9 is an enlarged, partial view of the perspective view of the probe holder portion of a console of FIG. 8.

FIG. 10 is a front view of the probe holder portion of a console of FIG. 8.

FIG. 11 is a back view of the probe holder portion of a console of FIG. 8.

FIG. 12 is a right side view of the probe holder portion of a console of FIG. 8.

FIG. 13 is a left side view of the probe holder portion of a console of FIG. 8; and,

FIG. 14 is a top view of the probe holder portion of a console of FIG. 8.

(Continued)

The portions of the figures depicted in broken lines, which illustrate a console and a probe, indicate an exemplary environment for the claimed design and do not form any part of the claimed design.
